UNITED STATES PATENT OFFICE.

HERMON W. LADD, OF CHELSEA, MASSACHUSETTS.

DESIGN FOR COT-BED BOTTOMS.

SPECIFICATION forming part of Design No. 12,618, dated December 20, 1881.

Application filed July 28, 1879. Term of patent 14 years.

To all whom it may concern:

Be it known that I, HERMON W. LADD, a citizen of the United States, residing at Chelsea, Massachusetts, have invented and produced a new, useful, and original Design for Cot-Beds, of which the following is a specification, reference being had to the accompanying drawings, forming part thereof.

Figure 1 is a perspective view of my newly-designed cot-bed, and Fig. 2 is a plan or top view of the same.

The characteristic feature of my design is the frame A, with rounded ends and straight parallel sides, having a raised curved head-board, E, at one end. The frame has a fabric or net-work, B, stretched from one end to the other, and is supported on legs C C, braced by diagonal rods. The ends of the fabric are concealed by the curved bands D.

A peculiarly light and graceful effect is produced by the construction shown in the drawings, the frame being open or without cross-pieces, and even the netted fabric B is wholly disconnected from the sides of the frame, as seen in both figures. The head-board E is

equally open, and in configuration and appearance conforms to the other parts. These features together constitute a unique design, light and graceful in appearance, and readily identified by the peculiarities referred to in the 30 claims.

The mechanical features of my invention are set forth in my patent of May 3, 1881.

I claim—

1. The design for a cot-bed herein shown and described, consisting of the frame having straight parallel sides and convex ends, supporting a fabric resembling netting stretched horizontally from end to end of said frame, and an open-work head-board.

2. The design for a cot-bed herein shown and described, embracing the frame A, with straight parallel sides and rounded ends, the fabric B, stretched from one of said ends to the other, the head-board E, and the legs C C.

HERMON W. LADD.
